UNITED STATES PATENT OFFICE.

MATHIAS LAUX, OF LITTLE ROCK, ARKANSAS, ASSIGNOR TO THE DOMESTIC GAS MANUFACTURING COMPANY, OF LITTLE ROCK, ARKANSAS, A CORPORATION OF ARKANSAS.

CARBURETER.

No. 927,558.

Specification of Letters Patent.

Patented July 13, 1909.

Application filed October 12, 1908. Serial No. 457,410.

To all whom it may concern:

Be it known that I, MATHIAS LAUX, a citizen of the United States, residing at Little Rock, in the county of Pulaski and State of Arkansas, have invented certain Improvements in Carbureters, of which the following is a specification.

This invention is an improvement in carbureters, and relates more especially to the provision of certain mechanism for the purpose of regulating the admission of air and hydrocarbon fluid to the carbureter proper, in connection with a particular arrangement of the several parts of the apparatus, including the disposition of the storage tank whereby the latter serves the two-fold purposes of storing a supply of the gasolene or hydrocarbon liquid and separating the residue from the volatile portion thereof.

20 The invention consists, therefore, in the particular construction and arrangement of the several parts, as hereinafter fully described and specifically set forth in the appended claims.

25 In the accompanying drawings, which form a part of this specification: Figure 1 is a front elevation of a carbureting apparatus constructed in accordance with my invention. Fig. 2 is a side elevation of the same. 30 Fig. 3 is a front elevation, showing in detail the mechanism for operating the fan or blower and the pump by which the gasolene or liquid hydrocarbon is fed to the carbureter. Fig. 4 is a plan view of the gearing mechanism between the spool or drum and the blower. Fig. 5 is a vertical sectional view through the mechanism shown in Fig. 3. Figs. 6, 7, 8 and 9 are details, hereinafter specifically referred to.

40 Like numerals of reference indicate like parts in all the figures of the drawings.

In carrying out my invention I preferably arrange the parts of the apparatus as shown in Figs. 1 and 2 of the drawings, and for this purpose provide a frame consisting of vertical end pieces 1, 1, connected by rods 2 and a top plate or platform 3; and having a forwardly projecting bracket 4 the outer end of which is braced by a curved arm 5. In the lower part of this frame is mounted a combined storage-tank and separator 7, supported at its rear end upon an upwardly-projecting flange 8 of the base of the supporting-frame, so that said tank and separator will be disposed at an inclination, for

the purpose hereinafter explained. Above the storage tank and separator, and between the end pieces 1, 1 of the supporting-frame, on inwardly projecting flanges 1^a thereof, is located a blower or fan 9, of ordinary construction, and upon the top-plate or platform 3 the carbureter tank 10 is mounted. This provides a very compact arrangement for the several parts of the apparatus, whereby such apparatus will not occupy very much space and therefore may be conveniently placed in the corner of a room out of the way but convenient to the points where the lights are to be located.

On the projecting end of the shaft 11 of the blower or fan is fixed a tappet-wheel 12, having radially projecting tappet-arms 13, and on said shaft is also mounted a pinion 14, in mesh with an idle gear wheel 15 driven by a gear wheel 16 on the shaft 17 which carries the spool or drum 18. This train of gearing between the fan-shaft and drum may be arranged to drive the fan at a different rate of speed from that of the drum. About the drum is wound a cord 19, which extends over suitable guide-pulleys and is connected to a weight 20, in the usual manner. The shaft of the drum is supported in the bracket 4 of the supporting-frame, and is extended beyond the same to receive a gear wheel 21 in mesh with a winding pinion 22 on a stub-shaft 23, the latter being squared at its outer end to receive a crank-handle.

24 designates a pump, the piston-rod 25 of which is connected to a lever 26 at one end thereof, the other end of said lever being fulcrumed in a standard 27 which rises from the inner end of the bracket 4 of the supporting-frame. The lever 26 is operated from the tappet-wheel by a shoe 28 pivotally connected at one end to a sleeve 29 on the lever and having its free end in the path of the tappet-arms 13. The shoe is adjustable, to increase or diminish the throw of the lever, and consequently the stroke of the piston of the pump, and this adjustment is accomplished by means of a threaded rod 30, pivoted at its lower end to the shoe and having its upper end passing through the lever and connected thereto by set-nuts 31 above and below said lever. The upper extremity of the rod is bent at right angles and reduced to form an indicating finger 32 which is adapted to travel over a graduated plate 33 fastened on the lever and projecting upwardly there-

from. This graduated plate is shown more clearly in Fig. 8, and it will be noted that by setting the rod, and consequently the shoe, the amount of liquid discharged through the pump can be regulated or graduated to suit different grades of gasoline, as indicated on the plate. For instance, in using a highly volatile hydrocarbon, as gasoline of 86 test, but a small quantity should be pumped into the carbureter at each stroke of the piston, while with a low grade of gasoline, for instance of 62 test, a larger quantity would be required at each stroke. By this arrangement, therefore, a person may easily adjust the mechanism according to the grade of gasoline that is being used with the apparatus. The pump receives the gasoline or hydrocarbon through a feed-pipe 34, which takes into the lower end of the tank 7 at a short distance above the bottom thereof, and in this feed-pipe is located an ordinary check-valve 35, to prevent back-pressure. The pump delivers to the carbureter through a supply-pipe 36, which latter is provided near the pump with an ordinary check-valve 36^a, and adjoining the carbureter with a bull-eye 37; the latter having a check-valve 38, seating downward, whereby a stand of gasoline or liquid is at all times retained in the vertical supply pipe 36. The bull's-eye provides a means whereby the amount of gasoline discharged to the carbureter on each stroke of the piston of the pump may be seen. The fan or blower is provided with the usual intake pipe 39, and with an air conducting pipe 40, the latter entering the carbureter near the lower end thereof, as is usual. The carbureter is provided near its upper end with an outlet or service pipe 41, for the carbureted air. There is also a drain pipe 42, extending from the bottom of the carbureter to the storage tank 7, said drain pipe extending vertically into said storage tank and having its outlet end near the lower end of said tank. As will be readily seen, the inclination of the tank provides a pocket at the lower end below the outlet pipe 34, and the heavy liquid or residue collects in this pocket, and by locating the lower end of the return or drain pipe 42 in this pocket it is at all times sealed against back pressure from the carbureter. The inclination of the storage tank provides that only a comparatively small amount of the liquid is required to form the pocket or seal. Entering this pocket or seal there is also an ordinary form of draw-off pipe 43, the upper end of which is provided with the usual cap 44 for connecting a draw-off pump thereto. The tank is also provided with a filling tube 45, and with a vent or petcock 46.

Having described my invention, I claim:

1. The combination with a carbureter, a supply tank for the hydrocarbon, a fan or blower, and means for operating the latter,

of a pump for forcing the hydrocarbon from the supply tank to the carbureter, a lever connected to said pump for operating the same, a shoe on said lever, and a tappet-wheel on the shaft of the fan or blower 70 adapted to engage the shoe for operating the lever.

2. The combination with a carbureter, a supply tank for the hydrocarbon, a fan or blower, and means for operating the latter, 75 of a pump for forcing the hydrocarbon from the supply tank to the carbureter, a lever connected to said pump for operating the same, a shoe on said lever, a tappet-wheel on the shaft of the fan or blower adapted to engage the shoe for operating the lever, and means for adjusting the parts with relation to the shoe and tappet-wheel, substantially as shown and described.

3. The combination with a carbureter, a supply tank for the hydrocarbon, a fan or blower, and means for operating the latter, 85 of a pump for forcing the hydrocarbon from the supply tank to the carbureter, a lever connected to the pump, a shoe on said lever, 90 a tappet-wheel driven by the means which operates the fan or blower, and adapted to engage the shoe for operating the lever intermittently, and means for adjusting said shoe with respect to the tappet-wheel. 95

4. The combination with a carbureter, a supply tank for the hydrocarbon, a fan or blower, and means for operating the latter, 100 of a pump for forcing the hydrocarbon from the supply tank to the carbureter, a lever connected to the pump, a shoe on said lever, 105 a tappet-wheel driven by the means which operates the fan or blower and adapted to engage the shoe for operating the lever intermittently, a rod connected to the shoe and adapted to adjust the same with respect to the tappet-wheel, and a scale-plate carried by the lever and co-operating with the rod to indicate the adjustment, substantially as shown and described. 110

5. The combination with a carbureter, a supply tank for the hydrocarbon, a fan or blower, and means for operating the latter, 115 of a pump for forcing the hydrocarbon from the supply tank to the carbureter, a lever connected to the pump, a shoe pivoted at one end to the lever, a rod attached to the shoe and adjustably connected to the lever and provided with a pointer, and a scale-plate attached to the lever so that the pointer of the rod will travel thereover; together with a tappet-wheel driven by the means which operates the fan or blower and adapted to engage the aforesaid shoe to operate the lever intermittently, substantially as shown and described. 120

6. In a carbureter, a supporting-frame having a forwardly projecting bracket, a fan or blower mounted in the supporting-frame, and means for operating said fan or blower sup-

ported by the bracket, a supply-tank for the hydrocarbon located in the frame below the fan or blower and disposed at an inclination, a carbureter mounted upon the supporting-
5 frame and having a drain-pipe extending into the supply tank to near the bottom of the lower end thereof, and a feed-pipe leading from the supply tank at a short distance above the lowermost end thereof; together
0 with a pump for forcing the hydrocarbon from the supply tank to the carbureter, a lever connected to the pump and having a

shoe, a tappet-wheel driven by the means which operates the fan or blower and adapted to engage the shoe to operate the lever in- 15 intermittently, and means for adjusting the shoe with respect to the tappet-wheel.

In testimony whereof I have signed my name to this specification in the presence of two subscribing witnesses.
